UNITED STATES PATENT OFFICE.

JOHN BURRY, OF RIDGEFIELD PARK, NEW JERSEY; MARIE BURRY EXECUTRIX OF SAID JOHN BURRY, DECEASED.

SELECTING DEVICE FOR ELECTRICAL SIGNALING APPARATUS.

No. 888,692.

Specification of Letters Patent.

Patented May 26, 1908.

Application filed July 18, 1906. Serial No. 326,675.

To all whom it may concern:

Be it known that I, JOHN BURRY, a citizen of the United States, residing at Ridgefield Park, in the county of Bergen and State of New Jersey, have invented certain new and useful Improvements in Selecting Devices for Electrical Signaling Apparatus, of which the following is a specification, reference being had to the drawings accompanying and forming a part of the same.

The subject of my present application is a combination of instrumentalities by means of which the electrical control of a number of remote devices, such as signal bells, printing magnets or the like may be readily and reliably effected, so that each or any of the same may be operated at will in any desired order or at any required intervals.

The improvement pertains to the general class of what may be termed selecting devices, and is designed for the ordinary purposes of such instruments. For example, in the operation of printing telegraphs, annunciators or any other system in which a certain number of mechanisms are required to be operated in a predetermined order, or an operation effected such as the printing of a character from a type-wheel while the latter is in any one of a given number of positions.

The object of the invention is to provide a simple and effective means for accomplishing this, and is or may be embodied in an apparatus of the following description.

A rotary drum is mounted to revolve in unison with a trailing contact, and is provided upon its periphery with a series of studs or projections set at definite and predetermined points. A plurality of contact terminals bear upon the drum, and when in contact with the surface of the same, complete branches of a controlling circuit, including an electro-magnet, but when raised from the surface of the drum, or, in general, while in engagement with the studs or projections these circuits are interrupted.

The trailer travels over a series of contacts known as a sunflower, the circuits of which are normally interrupted by the action of the controlling magnet, but any of the sunflower circuits may be closed at the instant when the trailer sweeps over the contact of such circuit by arranging the studs on the drum at a given point so as to interrupt the circuits

of all of the contact terminals and of the controlling circuit at the moment when the trailer is in the desired position, and thus breaking the controlling circuit so that the magnet therein permits the closure of the circuits of the sunflower. By different arrangements of the studs at different points on the drum and by shifting the position of the terminals upon which they operate, this action may be effected at any desired point in the travel of the drum and trailer.

Except in respect to the particular details hereinafter noted, the improvement is not limited to the specific construction, arrangement or operation of the devices which are shown and described in illustration of the same. I have, however, selected for purposes of such illustration the best and at the same time the most simple means of carrying out the invention of which I am at present aware.

In the drawings, Figure 1 is a diagrammatic illustration of the mechanism and circuit connections of the system in its entirety. Fig. 2 is a detailed view, partly in section, of the drum and one of the contact strips. Fig. 3 is a central longitudinal section of the drum and the parts rotating therewith. Fig. 4 is a diagram showing the different combinations of portions of the contact strips which determine the selection of the appropriate devices.

In the form in which my improvement is illustrated, the apparatus involves the use of a series of contact plates 1, each controlling one terminal of a circuit in which is included some electrical device to be operated from a remote point, and which, for purposes of illustration, I have represented as incandescent lamps 2. All of these lamp circuits run to a common generator 3, and are completed seriatim by the trailer 4, which is connected to the opposite pole of the generator 3. This arrangement is typical of the ordinary sunflower circuit controller, a type-wheel or a similar device, and may be varied within any limits permissible in such instruments. The disposition differs, however, from that ordinarily used in having in some part of the circuit common to all of the circuits 2 a controller consisting, preferably, of a circuit breaking armature 5, operated by a magnet 6 in an independent circuit.

On the same shaft 7 with the trailer 4 is a cylinder or drum 8, of conducting material, carrying a number of insulating studs or projections 9 arranged in certain definite positions, and bearing upon the cylinder are a series of contact strips 10, 11, 12, electrically connected together and included in the circuit with magnet 6, which contains also a local battery 13, and is in this particular instance completed through the shaft 7 and drum 8.

If the drum have a uniformly conducting surface, it is evident that the circuit including magnet 6 would always remain closed, 15 which, in the particular arrangement shown, would keep the circuits of the sunflower constantly interrupted. To break the circuit of magnet 6, therefore, at predetermined periods with reference to the travel of the 20 trailer 4, I employ the following means: The studs or pins 9 are set in the drum along lines corresponding in angular position to the position of the several contact plates of the sunflower. The arrangement of the studs 25 will be understood by referring to Fig. 4. Let it be assumed that in the first line, the studs are so placed as to interrupt the contact between the drum and the terminals either by raising all of the strips off from the 30 drum or otherwise. While these studs are under the strips 10, therefore, the circuit of magnet 6 will be broken and the circuit completed through that plate of the sunflower upon which the trailer rests. In all other 35 lines the studs are placed so that at least one of the strips 10, so long as they remain in the same position or condition, will be in contact with the drum and the circuit of magnet 6 will remain closed. In order, however, that 40 the interruption of the relay circuit may occur at other predetermined points during the travel of the trailer, I provide for the interruption of contact between all of the strips and the drum by different arrangements of 45 the studs in the other lines and by shifting the position of the strips. For example, in line 2 the studs are so placed that strips 10 and 11 will be raised by corresponding studs, but the third stud has been shifted out of the 50 normal line of strip 12 so that the latter will not be raised unless it is turned to one side or into the path of the displaced stud. It will be seen that this plan provides for various combinations, which are illustrated fully in 55 Fig. 4, and by means of which the circuit of the relay magnet can be interrupted in any of the positions of the drum 8 corresponding to those of the segments or plates of the sunflower. To shift the strips 10, 11, 12, I employ three magnets 15, 16, 17, with armatures 18, connected respectively with pivoted levers 19, carrying the strips as shown in Figs. 1 and 2. These magnets are included in three line circuits or branches of a 60 line circuit 20, and are controlled by keys 21.

By the depression of one, two or even three of these keys, or by leaving all of them up, a corresponding device 2 will be operated.

I have not deemed it necessary to illustrate or describe the means for rotating the 70 drum and trailer, nor to show the corresponding devices at the transmitting station, as these are all matters well understood in the art.

A greater number of strips may be used 75 and with each increase a greater number of possible combinations will be afforded. I may call attention to the fact that while I have shown devices for moving the strips bodily as the means of providing contacts in 80 different positions with respect to the drum, this is not necessary, as any means that will provide for the interruption or completion of contact between the several branches of the circuit of battery 6, at the points indicated 85 in the diagram of Fig. 4, may be employed.

Having now described my invention, what I claim is:

1. In an apparatus of the kind described, a selecting device comprising in combination, a 90 rotary drum having series of studs or projections at predetermined points on its periphery a controlling circuit with a plurality of terminals bearing on the drum, and means for varying the positions of such terminals 95 relative to their respective series of studs or projections on the drum, whereby the said circuit may be interrupted by the studs at any or all of the terminals in given positions of the drum, as set forth. 100

2. In apparatus of the kind described, a selecting device comprising in combination a rotary drum having series of studs or projections at predetermined points on its periphery, a controlling circuit, a plurality of terminal strips connected with the circuit and bearing on said drum, and means for shifting the position of said strips singly or in combinations relative to their respective series of studs or projections on the drum, whereby 110 the circuit may be interrupted by the engagement of the studs with any or all the strips in given positions of the drum, as set forth. 105

3. In apparatus of the kind described, a 115 selecting device comprising in combination a rotary conducting drum having series of insulating projections at predetermined points on its periphery, a controlling circuit, a plurality of terminal strips connected with the 120 circuit and bearing on the drum and normally closing such circuit while any one or more of the strips is in contact with the drum, and means for shifting the position of said strips whereby all of the same will be 125 raised from the drum by the projections at a given point thereon, as set forth. 120

4. The selecting device herein described, comprising in combination the rotary conducting drum having lines of insulating pro- 130

jections at predetermined intervals on its periphery, a controlling circuit, a plurality of contact strips connected therewith and bearing on the drum, and normally closing the 5 said circuit while any one or more of the strips is in contact with the drum, electromagnets for shifting the position of said strips whereby all of the same will be raised

from the drum by projections in different lines, and circuits including said magnets, as 10 set forth.

JOHN BURRY.
